(Cl. D61—1)

To all whom it may concern:

Be it known that we, William O. Schwartz and Grace B. Schwartz, citizens of the United States and residents of the city of Los Angeles, county of Los Angeles, State of California, have jointly invented a new, original, and ornamental Design for a Film Viewer, of which the following is a specification, reference being had to the annexed drawing, forming a part thereof, in which:

Fig. 1 is a top plan view of a film viewer showing our new design;

Fig. 2 is a bottom plan view;
Fig. 3 is a side view;
Fig. 4 is a rear end view; and
Fig. 5 is a front end view.
We claim:
The ornamental design for a film viewer, substantially as shown.

WILLIAM O. SCHWARTZ.
GRACE B. SCHWARTZ.
